RECORDING APPARATUS

Joseph William Miles, London, England, assignor
to International Business Machines Corpora-
tion, New York, N. Y., a corporation of New
York

Application October 4, 1934, Serial No. 746,866
In Great Britain October 5, 1933

3 Claims. (Cl. 234—59)

The present invention relates to recording apparatus, more particularly to apparatus for recording the working and non-working time of each of a number of machines.

It is desirable in any manufacturing industry to use the production machinery at its maximum in order that the factory may operate efficiently. To do this it is necessary to keep a record of idle and operating time of the various machines in order to facilitate the supervision of these machines. It is desirable to obtain the records from a plurality of machines at some central location. There are various machines at the present time which are designed to accomplish this, but they are generally handicapped, because of various obstacles, such as; (1) cost of suitable wire circuits having a line resistance sufficiently low to prevent undue voltage drop therein, (2) the cost of providing electromagnetic relays or the like for each of the production machines and, (3) the space taken up by a plurality of the electromagnetic relays and associated stamping means. If the normal commercial current supply of 110 to 220 volts is used in order to overcome the objection of line losses, the cost of properly insulated wiring circuit and contacts on the machines suitably insulated for this voltage, more than offsets the disadvantage that it seeks to overcome.

It is therefore an object of this invention to provide a recorder for producing a graphic record which will be operated on a low voltage system.

Another object is to provide a recorder operating on sufficiently low voltage and low flow of current to require only comparatively cheap wiring and contact structures.

Still another object is to provide a recording apparatus for graphically recording time without the employment of electromagnetic devices.

A still further object is to provide an apparatus for recording time on a chart without the use of type printing mechanism or ink applying mechanism.

A still further object is to provide a recording device for recording on a chart by electrolytic means.

Other objects and advantages of this invention will be apparent from the specification and the accompanying drawing which shows one embodiment of this invention and wherein the figure in the drawing represents a side elevation of the recording mechanism.

Referring to the preferred embodiment as shown in the drawing, an electrical contact associated with each of the production machines of which a record is to be kept may be arranged

as indicated at 30 which shows a 4-pole single throw knife switch which may be used to start and stop the machine in question. Two of the blades of said four pole switch serve to connect the driving motor 31 to the supply line 32, the other two blades serving to connect the secondary or low tension side of a transformer 33 to the recording apparatus.

In the drawing, A represents a terminal to which is connected one of the individual wires 10 running from the machine to the recorder. The other wire which as suggested may be a common return, from all machines to the recorder is connected to the terminal B.

The terminal A is connected by wire 1 to a 15 finger or needle 2, which is one of a large number of such needles carried by a frame 3, said frame being movable in a vertical direction in a manner to be described later. These needles are preferably arranged side by side adjacent the periphery 20 of drum 13 and longitudinal to it. The description hereinafter given applies to operation of one of these needles but it will be understood that all other needles of the set operate in an identical manner.

Frame 3 is connected to bell crank 4 pivotally mounted at 5 and biased in a counterclockwise direction by the weight of the frame 3 which extends the entire length of the drum. Due to this biasing action the end of the bell crank opposite 30 to the frame 3 rests against a cam 6. Cam 6 is fixed to a shaft 7 which is connected to a suitable time control mechanism such as a clock movement or an AC time controlled motor (not shown) so that shaft 7 is caused to revolve clockwise continuously at the rate of one revolution per minute. A cam 8 is also fixed to the shaft 7 and cooperates with a cam wiper 10 fixed to a lever 9 which is pivotally mounted at 11 and serves to raise and lower the lever 9 for each 40 revolution of said cam, said lever being biased in a counterclockwise direction by its normal weight. Pivotally mounted at one end of the lever 9 is a pawl 12 which coacts with a ratchet wheel 12a pivotally mounted at 14 and fixed to 45 pinion gear 14a. The pinion gear 14a meshes with a gear 15 which in turn meshes with a gear 16 which is fixed to the drum 13.

Thus the raising and lowering of the arm 9 imparts an intermittent uni-directional rotary 50 motion to the ratchet wheel 12a and thus to the drum 13.

The drum 13 carries a sheet of paper 13a impregnated with a chemical substance which, when in a damp condition, changes color, on the 55

passage therethrough of an electric current by electrolytic action. Suitable chemicals for this purpose are potassium iodide with starch or ferro-prussiate of potash.

- 5 It is necessary that the chemically impregnated paper should be damp at the moment when an electric current is to pass through it and for this purpose there is provided a roller 17 covered with a suitable fabric and mounted 5
- 10 on a link which in turn is pivotally mounted to one end of an arm 19, the other end of which is pivotally mounted at 20 and is biased in a counterclockwise direction by a spring 19a. Mounted 10
- 15 on the lever 19 is a cam wiper 20a which operates with a cam 21 fixed to the shaft 7 so that the rotation of the cam 21 oscillates the lever 19 back and forth. The roller 17 normally rests upon a strip of fabric 22 which is supported 15
- 20 on a table 22a running transversely of the machine and suitably supported by the framework thereof. The fabric 22 may be of any suitable material having good capillary qualities and extends into a tank 23 containing water. Upon 20
- 25 movement of cam 21 through approximately 90° from the position shown, roller 17 travels from the position shown in the drawing towards the left until it touches the surface of paper 13a thereby moistening the paper. At this time as 25
- 30 will be seen from the drawing the frame 3 is in its raised position by virtue of the motion of cam 6.

In addition to the needles 2 carried by the frame 3 there is provided an angle bar 24 extending transversely of the machine and pivotally supported on an insulated portion 25 of the frame 3. The vertical arm of this bar is parallel to the needles and makes contact with the paper 13a, at the same time that the needles 2 make contact, when frame 3 is lowered. The bar 24 40

40 is connected to return wire 26 which leads to terminal B aforementioned.

Each needle 2 is associated with some machine and is permanently connected by wire 1 to one of the blades of the four pole switch 30 45

45 associated with the machine, this last mentioned contact being closed when the machine is running and open when it is not.

If the shaft 7 is rotating, roller 17 will travel to the left on the surface of the fabric 22 till it 50

50 touches the surface of the paper 13a, dampening the same and will then recede. Frame 3 will then descend carrying the needle 2, and bar 24 with it so that they touch the damp surface of paper 13a. If the contact 30, to which needle 55

55 2 is connected, is closed, thus showing that the machine at which this needle corresponds is running, a circuit will be completed through the needle 2, the dampened paper 14 and bar 24. The consequent electrolytic action upon the 60

60 chemical substance with which the paper is impregnated will cause a change of color at the point of contact of needle 2 with the dampened paper 13a. After this has taken place, frame 3 rises and the drum 13 is rotated by means of the 65

65 action of cam 8 on the lever 8 as previously de-

scribed. Since the record upon the sheet 13a will agree with the shape of the end of needle 2 it will be possible to obtain records in the form of printed letters, figures or other symbols by forming the ends of the needles to the shape desired. In this way an accurate graphic record is obtained of the time and/or duration of the working of each of a number of machines and of the time during which each has been idle.

A comparatively low voltage only is necessary 10 to produce the requisite electrolytic effect referred to above.

While the fundamental novel feature of the invention as applied to a single modification has been shown and described and pointed out, it will 15 be understood that various omissions and substitutions and changes in the form and details of the device illustrated and in its operation may be made by those skilled in the art without departing from the spirit of the invention. I intend 20 to be limited therefore only as indicated by the scope of the following claims.

What is claimed is as follows:

1. In a time recording device, record receiving means comprising a chemically impregnated 25 chart, a timing device for moving said chart at a predetermined rate, means controlled by said timing device for periodically moistening said chart, and current conducting means moved into engagement with said moistened chart under 30 control of said timing device for effecting a recording operation by electrolytic action of the chemical in said chart.

2. In a time recording device, a chemically impregnated record receiving means, means for 35 periodically moistening said record receiving means over a predetermined area, contact members and means for periodically impinging said members against said moistened area of the record receiving means in timed relation to said 40 moistening means, and means for causing a flow of current through said contact members and said moistened area to effect a record on said record receiving means.

3. In a time recording device, record receiving 45 means including a chemically impregnated chart, a timing device for moving said chart, means for moistening said chart including a reservoir for holding a liquid, a moisture conducting element extending from said reservoir to a point 50 adjacent to said chart, a roller movable along said moisture conducting element and in contact therewith for picking up moisture from said element onto said roller, means controlled by said timing device for moving said roller along said 55 moisture conducting element and into contact with said chart to transfer moisture from said element to a portion of said chart; and current conducting means movable by said timing device into contact with the moistened portion of 60 said chart to effect a recording operation thereon by electrolytic action of the chemical in said chart.

JOSEPH WILLIAM MILES. 65
